UNITED STATES PATENT OFFICE.

WILLIAM E. CRANDALL, OF NEW YORK, N. Y.

PERAMBULATOR.

SPECIFICATION forming part of Letters Patent No. 668,728, dated February 26, 1901.

Application filed August 15, 1900. Serial No. 26,954. (No model.)

To all whom it may concern:

Be it known that I, WILLIAM E. CRANDALL, a citizen of the United States, and a resident of the borough of Manhattan, in the city of 5 New York, State of New York, have invented certain new and useful Improvements in Perambulators, of which the following is a specification, reference being had to the accompanying drawings, forming a part hereof.

10 This invention relates to reclining perambulators or wheeled chairs such as are commonly used for children and are provided with a hinged or swinging back and with a hinged or swinging foot or leg rest, so that 15 the occupant may recline at full length or sit upright, as in a chair.

The object of the invention is to provide improved connections between the back and the foot or leg rest, whereby the foot or leg 20 rest is raised or lowered to or from a horizontal position as the back is raised or lowered from or to a horizontal or a substantially horizontal position, such connections or means for moving and supporting the leg or foot rest 25 being so designed and arranged as not to interfere with the movement of the body of the perambulator with respect to the reach or running frame upon which it is yieldingly supported, while at the same time the desired 30 movement of the parts shall be easily effected and the parts be securely supported in the desired position.

The invention will be more fully described hereinafter with reference to the accompanying drawings, in which—

35 Figure 1 is a view in perspective of a perambulator to which the invention is applied in a convenient embodiment thereof, and Fig. 2 is a detail view of the locking means employed.

The particular form of the perambulator to which the invention is to be applied is immaterial, although it is preferable that the body should be spring-supported upon the reach or 45 running-frame. As shown in the drawings, the two parts or members A of the reach or running-frame have secured thereto the front and rear axles B and B', which receive the front and rear wheels C and C'. The body 50 D, which may be of any suitable or desired shape, is preferably secured to bow-springs,

one of which is shown at E, such springs being secured in turn to the respective members of the reach or running-frame A, so that the body has considerable freedom of movement with respect to the running-frame. The foot or leg rest F is pivoted or hinged to the forward portion of the body D, so that it may be lowered when desired from the substantially horizontal position shown in Fig. 1 to a 60 generally vertical position. The back G is likewise hinged or pivoted to the rear portion of the body D, so that it may be lowered from a substantially vertical position to or toward a substantially horizontal or inclined position, 65 and is preferably provided at each side with an extension or arm g. To the latter is pivoted, at each side of the perambulator, a rod H, which is extended forwardly and is supported by a link I, which is pivoted to the 70 rod at a point between its ends and may be pivoted upon the corresponding member of the reach or running-frame A at a point between the vertical planes which limit the movement of its other end, so that it supports the rod with a minimum of vertical displacement. To the end of each rod A is pivoted a link K, independent of the link I and connected pivotally with the foot or leg rest F, so that the thrust of the rods H is transmitted directly to the rest F through the links K, the links I serving only to support the rod. 75

It will be observed that when the back is in the position represented in Fig. 1 the foot or leg rest will be supported in a substantially 80 horizontal position, as also shown in said figure, and that when the back is moved to a substantially vertical position the rods H, swinging upon and with the supporting-links I, will draw the links K backward, permitting 85 the foot or leg rest to drop to a substantially vertical position. It will be evident, furthermore, that while the foot or leg rest is held firmly against falling accidentally, nevertheless, by reason of the support of the rods 90 by the links I, which are preferably inclined about as shown, the oscillations of the body with respect to the running-frame or reach will not be prevented or interfered with and such oscillation will not be liable to cause an 95 accidental falling of the foot or leg rest. Furthermore, by the described arrangement 100

of rods and links the desired movement of the foot or leg rest is easily effected as the position of the back is adjusted.

For the purpose of locking the back and the foot or leg rest in any desired position an arm L is secured to the back G at a point midway between its sides, such arm being preferably curved somewhat and being also somewhat elastic. The arm L is engaged by a suitable locking or clamping device carried by the body D and is preferably slotted, as at l, to straddle a threaded stud m, which is carried by a bar M of the body and receives a thumb-nut m'. By such means the back can be securely fastened in any desired position, the foot or leg rest being at the same time secured in a corresponding position.

I claim as my invention—

A perambulator comprising the front and rear wheel-carrying axles, the longitudinally-extending reach members connecting the said axles, a body, springs secured to the reach

members and supporting the body thereabove, a swinging foot-rest at the forward end of the body, a swinging back provided with downwardly-projecting lever-arms, longitudinally-extending connecting-rods pivoted at their rear ends to the lower ends of said lever-arms, supporting-links pivoted at their lower ends to the reach members, and at their upper ends pivoted to said connecting-bars near the forward ends thereof, and operating-links pivoted at one end to the forward extremities of the connecting-rods beyond the pivots of said supporting-links, and at their opposite ends pivoted to the foot-rest beyond its pivotal point; substantially as described.

This specification signed and witnessed this 9th day of August, A. D. 1900.

WILLIAM E. CRANDALL.
